UNITED STATES PATENT OFFICE.

WILKENS A. SCHENCK, OF PHILADELPHIA, PENNSYLVANIA, ASSIGNOR TO GABRIELLE
A. M. SCHENCK, OF PHILADELPHIA, PENNSYLVANIA.

COILED-SPRING HOLDING DEVICE.

1,281,851.

Specification of Letters Patent. Patented Oct. 15, 1918.

Application filed February 23, 1916. Serial No. 79,990.

To all whom it may concern:

Be it known that I, WILKENS A. SCHENCK, a citizen of the United States, residing in Philadelphia, Pennsylvania, have invented a 5 Coiled-Spring Holding Device, of which the following is a specification.

One object of this invention is to provide a holding device in the form of a helical coil which in one form shall be available for 10 use as a binding ferrule acting by virtue of its tendency to decrease its diameter after application to the object with which it is to be used.

It is further desired to provide a holding 15 device in the form of a coiled body, preferably of spring material under stress upon a suitably formed structure with which it is to coöperate so that it places said structure under compression and is frictionally held to 20 the same.

These objects and other advantageous ends I secure as hereinafter set forth, reference being had to the accompanying drawings, in which,

25 Figure 1 is a perspective view illustrating my invention as designed to serve as a ferrule for a tool handle;

Fig. 2 is an enlarged perspective view of the metallic coil illustrated in Fig. 1, and 30 shown as made of spring wire of circular section;

Fig. 3 is a perspective view of a spring ferrule similar to that shown in Fig. 2 except that its component wire is rectangular 35 in section.

In Figs. 1 and 2 of the above drawings 1 represents a wooden handle such as is used for holding files, chisels or similar tools, etc., and this is provided with a central longitudinally extending hole 2 in one end for the 40 reception of the tang of such a tool. Its end immediately adjacent this hole is of approximately cylindrical form and is preferably made with two radially extending kerfs or 45 cuts 3 formed at right angles to each other. In place of the cylindrical sheet or cast metal ferrule commonly mounted on this cylindrical portion 4, I provide a helical coil 5 of spring wire which may be of circular section 50 as shown in Fig. 2 or, as indicated at 5a in

Fig. 3, may be of some other section, such as rectangular.

It is to be understood that the coils are wound on a suitable mandrel or are otherwise so formed that their internal diameter is less than that of the portion 4 so that considerable force is necessary in order to apply them to it. In so forcing one of these coils into place it is necessarily expanded;—that is, it is unwound to a greater or less extent by reason of the forcible increase in its diameter. As a consequence, after being given 55 the position relatively to the handle shown in Fig. 1, it constantly exerts a compressing force upon the cylindrical end thereof, closing the cuts, if the wood is sufficiently flexible, and being capable of expansion when the tang of a tool is forced into the opening 2.

Under such conditions the coil acts at all 70 times to force the wood into the closest gripping engagement with said tang so that its unintentional removal is effectually prevented.

I claim:—

1. The combination with a tool handle having a central opening and kerfs formed in the end of the handle and extending radially of the opening, of a ferrule formed of convolutions of spring metal, said coils being 80 normally of slightly less diameter than that of the end of said handle whereby when the ferrule is forced upon the handle it is maintained under stress and compresses the divided end of said handle. 85

2. The combination with a tool handle having a central opening in one end thereof said end of the handle being longitudinally split and with the split portions extending radially of the opening, of a ferrule surrounding the split end of the handle and formed of a series of convolutions of spring metal, the normal diameter of the ferrule being less than that of the split end of the handle whereby when the ferrule is forced 90 upon the handle it is expanded and thereafter is maintained under stress around said split portion of the handle, said coil having its ends free and unconnected to said handle. 95

WILKENS A. SCHENCK.
